UNITED STATES PATENT OFFICE.

GREEN SMITH, OF PHILADELPHIA, PENNSYLVANIA.

CRATE.

1,232,987.

Specification of Letters Patent. Patented July 10, 1917.

Application filed October 13, 1915. Serial No. 55,706.

To all whom it may concern:

Be it known that I, GREEN SMITH, a citizen of the United States, residing at Philadelphia, in the county of Philadelphia and 5 State of Pennsylvania, have invented new and useful Improvements in Crates, of which the following is a specification.

This invention relates to crates and more particularly to collapsible crates or boxes 10 and has for its object the provision of a simple and efficient construction wherein the ends may be removed and the sides collapsed thereon and the cover adapted to retain the sides against spreading when the 15 crate is in operative position and hold the sides collapsed when the crate is folded.

Further objects of the invention will appear as the following description is read in connection with the accompanying drawing, 20 25 which forms a part of this application, and in which:—

Figure 1 is a perspective view,

Fig. 2 is a top plan view with the cover removed,

25 Fig. 3 is a vertical transverse sectional view taken on the line 3—3 of Fig. 1,

Fig. 4 is a vertical longitudinal sectional view taken on the line 4—4 of Fig. 1,

30 Fig. 5 is a perspective view of the crate in collapsed position, and

Fig. 6 is a view illustrating the auxiliary partition in its folded condition.

The improved crate includes a bottom section comprising a box-like member having 35 an open top.

The side flanges 2 of said bottom 1 have hingedly secured thereon, as at 3, foldable side members 4. The members 4 are of a length equaling the length of the sides 2, 40 and the hinges 3 are so arranged as to permit of the members 4 being folded over the end members 5 of the bottom 1, when the crate is collapsed. The numerals 6 designate the end members, the same having 45 their lower edges provided with dowel pins 7 which are adapted to be received in sockets 8 in the upper edges of the ends 5 of the base 1.

The ends 6 at their upper edges and adjacent 50 their ends are provided with pivoted spring catch members 9. Each of the catch members is preferably formed from a single strip of suitable material, such as wire, one of the ends of the same being bent and inserted in the upper edges of 55 the ends 6, so that the said members are

pivotedly connected with said sides, and the opposite or outer ends of said members are likewise bent to provide downturned tongues 10 which, when swung, are adapted to engage with the outer faces of the side members 4 and so retain the sides in a locked position upon the end members 6. The members 4 preferably have their outer corners notched, as at 4', to receive the tongues 65 of the spring catch members 9.

The sides 2 and the ends 5 of the lower section 1 are centrally provided with spaced cleats 11—11, arranged in pairs, the said cleats affording guideways for the opposite 70 ends of transverse partitions 12 and 13 respectively. The partition 12 preferably comprises a single member which is of a width equaling the distance between the sides 2 and the bottom section 1 as well as 75 the distance between the hinged side sections 4 connected with the said bottom section 1, and the partition 12 is centrally provided upon its opposite faces with cleats 14—14 to receive the inner ends of the 80 transverse partitions 13—13. It will thus be noted that the partition 13 comprises two separate members and each of the said members is centrally formed upon its opposite faces with spaced cleats 15—15 which align 85 with similar spaced cleats 16—16 upon the side members 2 of the base. Likewise the partition 12 centrally between its connection with the partition 13 and the side members of the crate is formed with spaced 90 cleats 17—17 registering with similar cleats 18—18 in the end members 5, and if desired, in the end sections 6 of the crate. All of these cleats are adapted to serve as 95 guideways for the ends of partition members 20. These partition members preferably comprise a plurality of hinged sections, four in number, which may be folded one upon the other, when not in set up position, and arranged within the lower compartment, when the crate is collapsed. The 100 numeral 21 designates the pivotal connecting member for the leaves of the partition members 20.

The crate, it will be noted, by the arrangement of the partition members 12 and 13 may have both its upper and lower sections divided into four separate compartments, preferably the partition 12 only projects above the lower section 1, but as 110 illustrated by the drawings the same may extend to the top of the crate, the same

having its outer edge in a plane with the outer edges of the upper section of the crate, and the members 20 divide the aforementioned compartments each into four 5 separate compartments, and so it will be noted that a great number of compartments are provided by the crate.

The side 2 of the bottom 1, below the 10 hinges 3, are formed with alining, substantially rectangular openings 22, and the sides 4 are likewise provided with similar openings 23.

The numeral 25 designates the flanged top or closure for the device. This closure has 15 two of its oppositely disposed flanges 26—26 provided with openings 27 which are adapted to register with the openings 23 when the crate is in its set up position or with the openings 22 when the crate is in 20 its collapsed position, and passing through the openings in said flanges 26 of the top or closure 25 and through either of the openings 22 and 23 are bars 28. Each of these bars has one of its ends formed with 25 an offset or angular portion 29, and its opposite end provided with an opening 30, and passing through the said openings and contacting with one of the flanges 26 is a securing element, preferably in the nature 30 of a cotter pin 31.

When the device is to be collapsed or folded the partitions 20 are swung against each other upon their pivots 21 and inserted in the lower flanged section 1. The partitions 12 and 13 are likewise arranged in the 35 said bottom section 1, as are the removable ends 6. The hinged members 4 are then swung over the upper edges of the flanged bottom sections 2, as illustrated in Fig. 5 40 of the drawings and the flanged closure 25 is arranged over the bottom 1. The openings 27 in the flanges 26 of the top member 25 are brought to aline with openings 22 in the side members 2 of the bottom, and the 45 bars 28 are passed through each pair of alining openings, and the cotter pins 31 are inserted through the openings 30 in the ends of the bars 28, thus locking the device in its knocked-down condition and securely 50 retaining the parts thereof in the bottom member 1 of the crate. The spring catch members 9 serve only to hold the members 4 and 6 in their upright condition so that proper articles may be introduced into the 55 crate, while the closure member 25 in combination with the bars 28 serve to retain

the crate in both its set up and knocked-down positions.

From the above description, taken in connection with the accompanying drawings, 60 the simplicity of the device, as well as the advantages thereof will, it is thought, be perfectly apparent to those skilled in the art to which such invention appertains without further detailed description. 65

Having thus described the invention, what I claim is:

1. A crate including a flanged bottom, side members hingedly connected with the bottom, removable end members upon the bottom, clamping means between the sides and ends, a flanged closure, removable means for securing the same to the crate, main partitions arranged one at a right angle to the other to divide the crate into compartments, 70 auxiliary partitions in each of the compartments, and each of said auxiliary partitions comprising a plurality of plates having their ends hingedly connected. 75

2. A collapsible crate including a flanged bottom having hinged sides secured thereto, removable ends upon the bottom, catch elements between the sides and ends, spaced cleats upon the flanges of the bottom, a partition engaging between two pairs of 80 oppositely disposed cleats, spaced cleats upon the said partition, second partition members engaging between the referred to cleats and the remaining cleats in the bottom section, auxiliary partitions comprising 85 a plurality of plates having their ends pivotally connected, whereby the said plates may be folded one upon the other and whereby the said plates may be swung and arranged between the flanges and the referred to partitions to produce auxiliary compartments in the crate, a flanged closure for the crate, means comprising bars passing through openings in the flanges of the said closure through openings in the hinged sides to 90 assist in maintaining the crate in its set up condition, and said bars designed to also pass through the openings in the flanges of the closure and through openings in the side members of the bottom to lock the crate in 95 its knocked-down condition. 100

In testimony whereof I affix my signature in presence of two witnesses.

GREEN. SMITH.
